UNITED STATES PATENT OFFICE.

ELZA N. HOWE AND HATTIE C. ARCHAMBEAU, OF PORTLAND, OREGON.

DESIGN FOR A MOTOR-CAR BODY.

47,233.

Specification for Design.

Patented Apr. 13, 1915.

Application filed December 8, 1914. Serial No. 876,150. Term of patent 14 years.

To all whom it may concern:

Be it known that we, ELZA N. HOWE and HATTIE C. ARCHAMBEAU, citizens of the United States, residing at Portland, in the county of Multnomah and State of Oregon, have invented a new, original, and ornamental Design for Motor-Car Bodies, of which the following is a specification, reference being had to the accompanying drawings, forming part thereof.

Figure 1 is a side elevation; Fig. 2 is a

rear elevation; and Fig. 3 is a front elevation, showing our new design.

We claim:

The ornamental design for a motor car body, as shown.
